LAWN SPRINKLER

Lewen R. Nelson, Peoria, Ill.

Application December 31, 1949, Serial No. 6,941

Term of patent 14 years

(Cl. D91—1)

To all whom it may concern:

Be it known that I, Lewen R. Nelson, a citizen of the United States, residing at Peoria, in the county of Peoria, and State of Illinois, have invented the new, original, and ornamental Design for a Lawn Sprinkler, and I do hereby declare that the following is a specification, reference being had to the accompanying drawing, forming part hereof.

Fig. 1 is a perspective rear view of a lawn sprinkler embodying my new design;

Fig. 2 is a top plan view of the same; and

Fig. 3 is a front elevation of the same sprinkler shown in Fig. 1.

The sprinkler portions shown in dotted lines in Fig. 1 have been omitted in Figs. 2 and 3 for convenience of illustration.

The dominant features of the design reside in portions shown in full lines.

I claim:

The ornamental design for a lawn sprinkler, as shown and described.

LEWEN R. NELSON.
